Attorneys.

UNITED STATES PATENT OFFICE.

JOHN SWAN, OF BALTIMORE, MARYLAND.

IMPROVEMENT IN SPORTSMEN'S POCKET-KNIVES.

Specification forming part of Letters Patent No. 149,806, dated April 14, 1874; application filed March 19, 1874.

To all whom it may concern:

Be it known that I, JOHN SWAN, of Baltimore, in the State of Maryland, have invented certain new and useful Improvements in Sportsmen's Implements; and do hereby declare that the following is a full, clear, and exact description thereof, reference being had to the accompanying drawings and to the letters of reference marked thereon, making a part of this specification.

My invention consists in a sportman's knife, having a round handle, with one solid smooth end, to form a cartridge-loader, hinged arms, provided with notched jaws, to form a cartridge-crimper and cartridge-extractor, and a sliding pin to form a cap-extractor, all as herein-after more fully set forth.

In order to enable others skilled in the art to which my invention appertains to make and use the same, I will now proceed to describe its construction and operation, referring to the annexed drawing, in which—

Figure 1 is a perspective view of my pocket-knife, and Fig. 2 is a side view of the same, showing it in the position of loading and crimping cartridges, and also in position for extracting cartridges.

A represents the knife-handle, made round in form, and one end, *a*, solid and straight, to form a convenient loader for cartridges. The outside diameter of the handle A should be such that the knife will easily pass into any of the paper cartridge-shells now generally used by sportsmen, whatever the caliber may be. The handle A contains one or more knife-blades, B, screw-driver C, cork screw D, and tweezers E, arranged in any desired manner. Through a central hole in the end *a* of the knife-handle passes a pin, *b*, attached to a slide within the handle, which slide has a spring-projection, *b'*, fitting in notches on one of the partitions in the handle to hold the pin either out or in. This pin forms the cap-extractor to punch the cap out of the head of the cartridge. At the opposite end *a'* of the handle are hinged two arms, G G, on opposite sides of the

handle. Each arm G is at its outer end provided with a jaw, G', the inner side of which is curved and provided with a sharp edge. The arms G G are of sufficient length that the inner edges of the jaws G' will come flush with the surface of the end *a* of the handle, and a circumferential shoulder is formed on said end for the jaws to rest upon. The arms G G being opened to allow the knife-handle A to be used as a loader, they are closed on the outside of the cartridge-shell and the jaws G' pressed against the shell, and the whole implement turned around. This crimps the shell immediately above the wad forced in by the loader, to prevent the same from coming out. On the outside of each jaw G' is a notch, *x*, so that the arms can be thrown over, as shown in Fig. 2, and used as a cartridge-extractor by the notches *x x* fitting over the flange of the cartridge-head. The inner sides of the arms G G are roughened to form file-surfaces.

Having thus fully described my invention, what I claim as new, and desire to secure by Letters Patent, is—

1. A sportsman's pocket-knife, formed with a round handle, it having a solid smooth end, *a*, to form a cartridge-loader, substantially as herein set forth.
2. The hinged shell-crimping arms G G provided with jaws G' G', in combination with the round-handled knife A, substantially as and for the purposes herein set forth.
3. The notches *x* formed in the back of the jaws G', forming a cartridge-extractor, for the purposes herein set forth.
4. The cap-extracting sliding pin *b*, in combination with a round-handled knife, substantially as for the purposes herein set forth.

In testimony that I claim the foregoing I have hereunto set my hand, this 12th day of March, 1874.

JNO. SWAN.
